(No Model.)

J. HOPSON, Jr.
RADIATOR.

No. 378,093.

Patented Feb. 21, 1888.

UNITED STATES PATENT OFFICE

JOHN HOPSON, JR., OF NEW LONDON, CONNECTICUT.

RADIATOR.

SPECIFICATION forming part of Letters Patent No. 378,093, dated February 21, 1888.

Application filed March 23, 1887. Serial No. 232,119. (No. model.)

To all whom it may concern:

Be it known that I, JOHN HOPSON, Jr., of New London, county of New London, and State of Connecticut, have invented certain new and useful Improvements in Radiators, of which the following is a full, clear, and exact description, reference being had to the accompanying drawings, and to the letters of reference marked thereon.

10 My invention has relation to radiators such as are employed for heating purposes in connection with steam, water, or other heat-conveying fluids or liquids.

15 The object of my invention is to produce a radiator of thin material which shall be amply strong and durable, in which the joints are easily and cheaply made, presenting a smooth exterior or finish, and not subject to damage when the radiator is emptied, which 20 may present an enlarged exterior surface for radiation of heat and a correspondingly large interior surface for contact of the medium with the material of which the radiator is made, and which shall secure other advantages in the matter of construction, locating 25 or mounting, finish, and operation.

To accomplish all of this my improvements involve certain new and useful peculiarities of construction and arrangements or combinations of parts, which will be hereinafter fully described, and then pointed out in the claim.

30 In the accompanying drawings, forming part of this specification, Figure 1 is a view partly in side elevation and partly in vertical section, showing a radiator constructed in accordance with my invention and involving my improvements. Fig. 2 is a sectional elevation upon a plane at right angles to that of Fig. 1, and Fig. 3 is a cross-section of one of 35 the vertical radiating-tubes. Figs. 4 and 5 are like Figs. 2 and 3, except that the headers and vertical tubes are shown plain or cylindrical instead of fluted or corrugated. Fig. 6 is a sectional elevation like Fig. 2, except that it shows two sets or rows of vertical 40 tubes united to form the radiator, and is intended to indicate that any number of rows may be employed. Fig. 7 is a cross-section and elevation of the upper part of the double 45 radiator, showing the method or means employed for bracing the rows; and Fig. 8 is a side view of a fragment of the upper part,

showing the washer used to cover the screw-ribs when not in use. Figs. 9, 10, and 11 are sectional views showing different forms of 55 joints which may be employed for uniting the vertical tubes and headers. Fig. 12 shows a section and elevation of a tube of different form from those of previous figures, which may be used in the radiator, and is intended to indicate that a variety of forms or designs may be employed.

In all the figures like letters of reference, wherever they occur, indicate corresponding parts.

60 A A are the horizontal tubes or pipes, called the "headers," and serving to unite the vertical tubes B B, from which the greatest amount of radiation takes place. These tubes and the headers as well are all made of 70 thin metal, and preferably of brass or equivalent metal, easily drawn, and they may be drawn in such manner as to present a fluted, corrugated, or otherwise extended or enlarged exterior surface, by which radiation is increased, as is well understood.

65 In Figs. 1, 2, 3, and 6 the flutings a a, &c., extend in straight lines in the direction of the axes of the tubes and headers. In Fig. 12 the corrugations b b extend spirally around 75 the tubes. In other figures the tubes are all plain or smooth inside and out. The varieties shown are deemed ample to indicate that the patterns of the surface may be variously modified, as I intend they shall be, though I 80 prefer to make the headers and the uprights of like pattern, so as to secure that general harmony throughout which is in accordance with the prevailing modes of decoration or ornamentation. The plain and the fluted may, 85 however, be combined in any desired way.

90 By fluting or corrugating the thin metal pipes the interior surface is extended or enlarged the same as the exterior, so that the heat-conducting medium is brought into contact with a larger surface, and much more directly in contact with the radiating material than in those styles employing disks or projecting points, which are cast or otherwise formed upon a pipe having a regular or 95 smooth interior. The advantage of thus bringing the heat-conducting medium nearer to the entire exterior surface will be readily appreciated. The metal employed is quite

thin. It is thus easier drawn, it gives up its heat very rapidly, and it makes the structure very light and easy to be mounted in its place and easy to be handled during the construction and finishing. All desired strength and rigidity are contributed by the flutings or corrugations, if they be employed.

Heretofore it has been customary to thread the vertical tubes into the headers. This necessitated the employment of heavy or thick metal throughout, in order to provide for the threads, or at least a special enlargement of the parts in the region of the joints, all of which were expensive and difficult to make. Further than this, the threaded joints deteriorate by rusting when the radiator is not in use or when emptied, leaving it in an unsafe condition, and they present a rough and uneven exterior, not only unsightly, but difficult and expensive to smooth off or finish, as is necessary if plating or such like finishing be desired. To obviate these disadvantages I unite the parts entirely by soldering, (or brazing,) leaving the exterior smooth, the joints sound, perfect, and durable, without increasing the thickness of metal and at very much less expense than in previous constructions, and when the parts are thus united the radiator is ready for the plating-bath without other preparations than the usual cleaning. It is inserted in the bath bodily after the parts are united. The brass is found to hold the plating well when the radiator is used, whereas any plating upon iron rapidly deteriorates under the influence of the heat to which it is subjected.

Within the ends of the headers the blocks, as *c d*, are soldered, *c* being intended to receive an air-valve and *d* an inlet or outlet pipe for the steam or water. Two or more rows of vertical tubes, each row having top and bottom headers, may be united in one structure, provisions being made for cross-circulation at top and bottom. At *e e*, Fig. 6, cross-connections are shown in dotted lines. These may be short tubes soldered into the headers or into the end blocks, as may be desired. To cover the ends, removable shells or caps, as *f f*, may be slipped upon the headers.

To sustain the radiator above the floor, I provide feet, as at *g g*, which are fashioned at top to receive the lower headers, (of whatever number they may be,) and they are secured to the lower headers by bolts, as *h h*, and nuts thereon. The bolts are soldered to the under surfaces of the lower headers, and the feet may be screwed to the floor, if desired.

Various kinds of unions between the vertical and horizontal pipes may be employed. The vertical may be slipped into the hori-

zontal, as in Fig. 1, or over a short collar formed integral with the horizontal, as in Fig. 9, or over an inserted collar, as in Fig. 10; or the end of the vertical pipe may be expanded inside the horizontal, as in Fig. 11. In either 65 or any form the joint is to be secured by soldering, (or equivalent brazing.)

When two or more rows are employed in the radiator, they should be braced together at top. For this purpose I supply the upper 70 headers with short threaded nibs, as *i i*, on each side. Two opposite nibs present right and left threads, and they are joined by any connecting pieces or braces, as *k*, which draw the headers to the proper position and firmly brace 75 them. When the nibs are not used, as those on the exterior, they are covered by an ornamental removable washer, as *l*. The nibs are soldered on the headers and on both sides of each, so that all will be alike.

The radiator thus constructed is found to admirably answer the purpose or object of the invention as previously set forth.

I am aware that thin-metal radiators are in common use, and that the use of solder for 85 closing joints in sheet-metal structures is an ordinary expedient, and I make no claim except to a construction of a radiator that dispenses with screw-thread connections that necessitate an opening in the wall of the radiator, and that also obviates the necessity of piercing any portion of the same to provide means for its proper support either vertically or laterally.

Having now fully described my invention, 95 what I claim as new, and desire to secure by Letters Patent, is—

As a new article of manufacture, a radiator composed of thin-metal upper and lower headers with end plugs covered by caps and 100 vertical connecting-tubes, the upper headers having nibs and connecting-braces on adjacent sides, and the lower headers having supporting-legs holding them in fixed relation to each other, said nibs having a connection of solder 105 with the upper headers, and said legs secured by bolts having a connection of solder with the lower headers, whereby screw-thread connections and unnecessary joints are obviated and the upper and lower parts of the radiator are secured and held, all substantially as specified.

In testimony that I claim the foregoing I have hereunto set my hand in the presence of two witnesses.

JOHN HOPSON, JR.
